(57) **CLAIM**

The ornamental design for a footwear sterilizer for vehicles, as shown and described.

DESCRIPTION

FIG. 1 is a top, front, right perspective view of a footwear sterilizer for vehicles, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a top, front, right perspective view of the footwear sterilizer for vehicles, shown in condition of use for clarity of disclosure.

In the drawings, the equal-length broken lines depict portions of the footwear sterilizer for vehicles that form no part of the claimed design. In FIG. 8, the broken lines showing a vehicle seat depict environmental structure and form no part of the claimed design. All broken lines form no part of the claimed design.

1 Claim, 8 Drawing Sheets
